UNITED STATES PATENT OFFICE.

JOHN W. PATTERSON, OF OKLAHOMA, OKLAHOMA.

BED ATTACHMENT.

1,363,430.

Specification of Letters Patent. Patented Dec. 28, 1920.

Application filed April 10, 1920. Serial No. 372,861.

To all whom it may concern:

Be it known that I, JOHN WILLIAM PATTERSON, a citizen of the United States, residing at Oklahoma city, in the county of 5 Oklahoma and State of Oklahoma, have invented certain new and useful Improvements in Bed Attachments, of which the following is a specification, reference being had to the accompanying drawings.

10 This invention relates to certain improvements in bed attachments, and it is an object of the invention to provide a novel and improved attachment constituting a child's bed and which, when not in use, may be 15 readily concealed.

It is also an object of the invention to provide an attachment of this general character which is slidably engaged with a trackway disposed transversely of the bed 20 and positioned therebeneath, said attachment constituting a child's bed and being readily collapsible so that the same may be forced inwardly of the trackway, when collapsed, and be concealed beneath the bed 25 and which, when in an outward position, may be readily extended into an assembly for sleeping purposes.

The invention consists in the details of construction and in the combination and arrangement 30 of the several parts of my improved attachment whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the 40 better understood, I will now proceed to describe the same with reference to the accompanying drawings, wherein:

Figure 1 is a view in side elevation, illustrating a bed attachment constructed in accordance with an embodiment of my invention and in extended position;

Fig. 2 is a view in top plan of the structure illustrated in Fig. 1;

Fig. 3 is a view partly in horizontal section and partly in top plan, illustrating a bed attachment constructed in accordance with an embodiment of my invention and in concealed position; and

Fig. 4 is a sectional view taken substantially on the line 4—4 of Fig. 3.

As disclosed in the accompanying draw-

ings, B denotes a bed of a standard size and suspended below the side rails 1 thereof through the instrumentality of the brackets 2 are the tracks 3, extending transversely 60 of the bed and in parallel relation. Each of the tracks 3 is U-shape in cross section with its open face inwardly disposed. F denotes a frame, preferably oblong in form, and having its major diameter disposed longitudinally of the bed B and of a length whereby said frame F may snugly engage within the tracks 3 for sliding movement therealong. Connecting side members 4 of the frame F are the crossed bracing members 5 whereby said frame F is materially strengthened. Disposed through the side members 4 of the frame F adjacent the opposite ends thereof and bridging the space therebetween are the rods or shafts 6, each 70 capable of rotary movement. The rods or shafts 6 extend a desired distance outwardly of the frame F to provide the extensions or arms 7 and the outer end of each of said arms or extensions 7 is provided with a leg 8, substantially at right angles thereto, and which serves as a supporting means for the attachment when the same is in its extended position and in an assembly for occupancy by an infant.

Operatively engaged with each of the extensions or arms 7 is an end frame E of a collapsible bed structure, said end member being disposed in a direction opposite to the supporting leg 8 so that when the end 90 of the frame E is in a substantially vertical position, the supporting leg 8 is arranged for contact with the floor or other surface.

Each of the end frames E includes the side members 9 and the inner side member, 95 when the structure is collapsed and the end frame in substantially a horizontal position or in a position co-planer with the frame F, rests within a supporting bracket 10 carried by the outer side member 4 of the frame F. 100 This bracket also serves as a stop to limit the inward or collapsing movement of the end frame.

The side members 9 of the end frames E, at a point in close proximity to the extensions or arms 7, are provided with the inwardly disposed brackets 11, each substantially in the form of an inverted triangle and having its upper portion 11^a substantially perpendicularly related to the coating 110 side member 9. Supported by the inner end portions of the pair of brackets 11 carried

by each of the end frames E is a transversely disposed rod 12 which is also freely disposed through the slots 14, disposed longitudinally of a spring frame S and which frame is of 5 a length slightly less than the distance between the extensions or arms 7. By this connection, as the end members E are swung inwardly, the spring frame S will be lowered into a position below the frame F so 10 that as said frame F is moved inwardly of the tracks 3, the attachment or collapsible bed structure will be concealed beneath the bed B. When the end members E are swung upwardly, the spring frame S will be raised 15 into the requisite position to receive the infant.

The outer side members 9 of the end frames are provided with the inwardly facing guide members 15 extending longitudinally thereof and substantially U-shape in cross section and in which is adapted to be slidably and removably engaged the end portions of a side panel P. The side panel P, when applied, operates to hold the end members E from collapsing or folding inwardly while the spring frame S operates to limit the outward or upward swinging movement of said side members. When the attachment is to be collapsed, the side panel P is removed 25 and preferably placed upon the spring frame so that when the structure is collapsed, the same will be carried by the spring frame S whereby the panel P is at all times accessible. The spring frame S, at desired 30 points thereon, is provided with suitable clamps 16 to hold the bedding thereto and said clamps 16 may be of any character or type preferred.

I also find it of advantage to provide the 40 outer ends of the supporting legs 8 with the feet 17 threaded or otherwise adjustably engaged therewith whereby the attachment or collapsible bed structure may be adjusted with respect to standard beds of different 45 heights and particularly as may be occasioned by the bedding arranged thereon. It is also to be understood that when the at-

tachment or foldable bed structure is in extended or operative assembly, the spring frame S is substantially flush with the standard bed so that a mother, or the like, within the standard bed may have ready and convenient access to the infant occupying the attachment or collapsible bed. 50

From the foregoing description, it is 55 thought to be obvious that an attachment constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself 60 to the precise arrangement and formation of the several parts herein shown in carrying out my invention in practice except as hereinafter claimed. 65

I claim:—

A bed attachment comprising tracks adapted to be secured transversely beneath a bed, and a collapsible and slideable bed structure adapted to be disposed beneath the bed or to be erected at a side thereof, 70 said structure comprising a frame slideable along the tracks, shafts rotatably supported by the frame and extending beyond the side thereof, the outer extremities of the extended portions of the shafts having lateral extensions serving as supporting legs when the structure is erected, inwardly disposed and transversely spaced brackets carried by the end frames, a rod connecting the brackets of each end frame, and a member interposed between the end frames and provided with longitudinally disposed slots adjacent its opposite ends and through which the rods are freely directed whereby said member is raised or lowered upon requisite movement 85 of the end members. 90

In testimony whereof I hereunto affix my signature.

JOHN W. PATTERSON.
